Primary Examiner — Catherine A Tuttle(57) **CLAIM**

The ornamental design for a sprayer, as shown and described.

DESCRIPTION

FIG. 1 is a front elevational view of a sprayer showing my new design;

FIG. 2 is a rear elevational view thereof;

FIG. 3 is a left side view thereof;

FIG. 4 is a right side view thereof;

FIG. 5 is top plan view thereof;

FIG. 6 is a bottom plan view thereof; and,

FIG. 7 is a perspective view thereof.

The broken lines shown in FIG. 6 are included for the purpose of illustrating the bottom surface portion that forms no part of the claimed design.

1 Claim, 6 Drawing Sheets(56)
